his Atty.

UNITED STATES PATENT OFFICE.

FREDERICK CARL, OF WASHINGTON, DISTRICT OF COLUMBIA, ASSIGNOR TO
ERIC M. NOBLE AND WILLIAM A. RABORG, OF SAME PLACE.

DEPOSIT-BOX.

SPECIFICATION forming part of Letters Patent No. 425,491, dated April 15, 1890.

Application filed October 1, 1889. Serial No. 325,651. (No model.)

To all whom it may concern:

Be it known that I, FREDERICK CARL, a citizen of the United States, residing at Washington, in the District of Columbia, have invented 5
certain new and useful Improvements in Deposit-Boxes; and I do hereby declare the following to be a full, clear, and exact description of the invention, such as will enable others skilled in the art to which it appertains to 10
make and use the same.

My invention relates to a safety-receptacle for valuables, packages, letters, and similar articles; and my object is to produce a cheap, strong, durable, and safer device than those 15
hitherto in use.

With this end in view my invention consists in the peculiar features and combinations of parts more fully described hereinafter, and pointed out in the claims.

20 In the accompanying drawings, Figure 1 represents a side elevation in section of my complete device; Fig. 2, a front view, partly in section, and Fig. 3 a detail sectional view, of the top part of the chute and the guard.

25 The reference-letter *a* represents the box or receptacle, which may be of any suitable size or shape, with a sloping top *a'*, having therein a transverse opening *b* for the reception of the articles to be inserted. In the present instance

30 the slot is made long and narrow, for the purpose of receiving envelopes and the like. A chute *c* is pivoted off its center by means of a pivoted bar *d*, operating and supported in the hangers *d'*. This chute is given a length suffi-

35 cient to receive the articles intended for it, and is closed upon all four sides, excepting the top and bottom, which are left open. A cut-off plate *e* is secured to the lower ends of the hangers *d'* and placed across the interior of the box 40 below the lower end of the chute to close it when the upper end is thrown in open adjustment. The upper end of the chute is provided with a cut-off plate *f*, which extends laterally from the top of the chute and closes the open-

45 ing *b* when the chute is not in receiving position. The guard *f'* extends around the under side of the opening *b* and down into the box to form a close connection with the upper surface of the cut-off plate *f*, whereby the contents of the box are more perfectly protected

from pilfering. A pair of stops *g* extend down from the top of the box to limit the backward play of the chute, while a projection *f''* upon the back edge of the top of the chute comes in contact with the guard and limits its forward play. This lug also serves as a frictional bearing-surface for the chute-actuating arm *h*, which extends down from the cover *i*. This cover is pivoted just above the slot and beneath the water-shed *k*. The lower edge *i'* of the cover is curved slightly upward to permit it to be raised by sliding the matter in under it, and the cover is so weighted as to drop down over the slot by its own weight when released.

55 The lower end of the pivoted chute is made 60 heavier than its upper end, in order that it will drop by its own gravity against the stops and normally keep the opening *b* closed, as shown in dotted lines in Fig. 1. It will be seen that the entire chute and its co-operating 65 mechanism are secured to the top of the receptacle.

In operating my device the depositor raises the cover *i* by sliding the matter up under it, or by lifting it, which operation causes the arm 70 *h* to engage the lug *g* and force the upper light end of the chute forward until arrested by the opposite side of said lug coming in contact with the guard. When tilted to this position, the bore of the chute will be brought into coincidence with the receiving-opening *b* to receive the matter deposited, while the lower end of the chute will pass over the cut-off plate *e* and cut off access to the interior of the box, 75 as shown in Fig. 1. The moment the depositor 80 releases the gravitating lid or cover the heavier end of the chute will drop down against the stop and away from the cut-off plate, thereby opening the bottom of the chute and permitting its contents to drop into the box, as 85 indicated by dotted lines, and when in this position the upper cut-off plate *f* comes over the receiving-slot *b* and makes the interior of 90 the receptacle perfectly inaccessible.

95 It is evident that many slight changes which might suggest themselves to a skillful mechanician could be resorted to without departing from the scope and spirit of my invention. Therefore I do not limit myself to the exact construction shown.

Having thus described my invention, what I claim as new, and desire to secure by Letters Patent, is—

- 5 1. In a receptacle having a receiving-opening, the combination of a pivoted chute having one end heavier than the other and arranged to coincide with said opening, a cut-off plate over which the open end of the chute passes and becomes closed when the chute is brought into coincidence with the receiving-opening, and a lid or handle for tilting the chute, substantially as described.
- 10 2. In a receptacle having a receiving-opening, the combination of a pivoted chute arranged to coincide with the opening, a cut-off

plate over which the open end of the chute passes and is closed when brought into coincidence with said opening, a cover adapted to close the opening when the chute is not in receiving position, and an arm connected with the cover and arranged to engage the upper end of the chute to throw it into coincidence with the opening when the cover is raised, as and for the purpose set forth.

In testimony whereof I affix my signature in presence of two witnesses.

FREDERICK CARL.
